UNITED STATES PATENT OFFICE

CHARLES THOMAS POWERS, OF BRISBANE, QUEENSLAND.

TYPE-WRITING MACHINE.

SPECIFICATION forming part of Letters Patent No. 661,551, dated November 13, 1900.

Application filed December 5, 1898. Serial No. 698,322. (No model.)

To all whom it may concern:

Be it known that I, CHARLES THOMAS POWERS, gun and rifle maker, residing at Albert street, Brisbane, Queensland, have invented 5 certain new and useful Improvements in Type-Writing Machines; and I do hereby declare the following to be a full, clear, and exact description of the invention, such as will enable others skilled in the art to which it applies to make and use the same.

My invention has relation to type-writing machines, and more especially to that type of machines wherein the impressions are obtained from a so-called "type-wheel" having 15 one or more circular rows or fields of type—as, for instance, small-case, capitals, and figures and symbols.

My improvements relate more particularly to the mechanism for positioning the type-wheel to make an impression, and to effect this in the known machines the following, among other parts, have been necessary, namely: a ratchet or sprocket wheel; a stop-plate therefor and two screws; a second heart-shaped ratchet or sprocket wheel and a shield therefor; a front-stop plate and two rivets; a front-stop spring and spring-stud and a front-stop adjustment and nut; a back-stop bail, bail-plate, and two screws; a back-stop 25 bail-spring and stud and back-stop adjustment screw and nut; two back-stop-holding plates and four screws; a main action-spring, main action-spring stud or main action-spring tension-crank and screw.

My invention has for its object the simplification of the above-described mechanism by dispensing with the twenty-nine elements enumerated and substituting the following 35 six elements: a stop-wheel, a locking device therefor and a retracting-spring, a stop-guide, a cam-lever, a lever actuated thereby, and a fulcrum-screw for said lever. In lieu of the spring heretofore used for returning the type-wheel rock-shaft into a normal position and attached to the upper frame and to a comparatively long radial arm on a sleeve on said shaft I mount said spring on the shaft itself.

That my invention may be fully understood 45 I will describe the same in detail, reference being had to the accompanying drawings, in which—

Figure 1 is a top plan view of a wheel type-writing machine, the general construction of which is well known, embodying my improvements, the type-wheel being shown depressed as in the act of making an impression. Fig. 2 is a fragmentary cross-sectional view taken on or about on line 1 1 of Fig. 10. Fig. 3 is a sectional detail view showing the normal relative positions of those parts which constitute my invention, the stop lock-wheel being shown partly broken away. Fig. 4 is a view similar to Fig. 2, the section being taken about on line 3 3 of Fig. 10. Fig. 5 is a view similar to Fig. 3, showing the parts viewed from the right-hand side of the machine. Fig. 6 is a view similar to Fig. 2, the stop lock-wheel being shown in section and the type-wheel in the position it assumes when a key has been 55 partly depressed to revolve said wheel, and thereby position the particular letter, figure, or symbol for printing, the parts being shown approximately in their relative positions. Fig. 7 is a fragmentary detail sectional view 60 of Fig. 6, some of the parts being partly broken away. Fig. 8 is a view similar to Fig. 6, showing the type-wheel fully depressed. Fig. 9 is a fragmentary sectional detail view 65 of Fig. 8. Fig. 10 is a front elevation of a portion of the upper machine-frame and parts mounted therein. Figs. 11 to 15 are detail perspective views of the six mechanical elements 70 above referred to and of the type-wheel-bearing sleeve that also actuates the feed mechanism for the platen and paper carriage, showing the same provided with a slotted guide-arm for the locking dog or pawl that co-operates with the stop-wheel to lock the type-wheel in position for printing. Fig. 16 is a cross-sectional view of the machine, illustrating a modification of the means for operating the locking-pawl; and in Fig. 17 I have shown a modified mode of connecting the actuating-rod with said pawl.

As hereinbefore stated, my improvements relate to wheel type-writing machines of well-known construction. It will therefore not be necessary to describe in detail all of the parts of the machine, which will only be briefly referred to, with the exception of those parts with which my said improvements are directly connected.

In the drawings, F indicates the main fram-

ing, and f the upper frame part, in which is journaled the type-wheel rock-shaft S . The key-levers L are arranged in superposed banks, (three in the example shown in Fig. 1,) each bank being divided into two groups on either side of the central line of the machine intersecting the axis of rotation of the type-wheel W and on either side of a spacing-lever L' , arranged in or substantially in said central plane. The key-levers have hooked ends l , hooking on a fulcrum-rod R , common to all the levers, and said key-levers have bearing-shoulders $2, 3$. The shoulders 2 have bearing on rocking frames or short bails b —one for each group of key-levers on either side of the spacing-lever L' —while the shoulders 3 are adapted to bear on and depress a rocking frame or long bail b' . The key-lever shoulders or bearing-surfaces 2 are all alike in position, while the relative position of the shoulders or bearing-surfaces 3 varies, so that in a line of keys they will be graded consecutively for well-known purposes.

The key and spacing levers are guided in comb-plates p and p' , and the platen P is mounted on a suitable carriage receiving its progressive or feed motion from a radial arm s' on a sleeve S' , Fig. 11, which in accordance with my invention has a second angle-arm s^2 , provided with a guide-slot s^3 for the type-wheel-locking pawl hereinafter referred to, and to the horizontal member of said angle-arm s^2 , proximate to the forward end of the slot s^3 , is secured in accordance with my invention a retarding-spring S^2 , hereinafter referred to, said sleeve S' having bearings, one, s^4 , at the heel of angle-arm s^2 , and one, s^5 , axially and transversely of the sleeve for the type-wheel spindle S^3 , which extends, as usual, through the rock-shaft S , and thus also locks the sleeve S' against rotation thereon. There is also provided the well-known mechanism for shifting the type-wheel spindle S^3 in its bearings to bring one or the other field of type into position for printing, the inner end of said spindle extending through a bracket 4 and carrying a lock-nut 5 , said bracket having sliding motion in the slot of a suitable guide, the spindle being retracted by a suitable spring 6 , the appliances for shifting said type-wheel spindle being controlled by special key-levers in a well-known manner.

The type is inked by a roller journaled in an arm depending from the loop or bail f' on the upper frame portion f , in which loop the type-wheel vibrates.

Finally there are provided the usual sector-levers operating a pinion rigidly connected with the type-wheel and controlled by the type-key levers in a well-known manner and hereinafter to be referred to.

All of the parts above described, with the indicated exceptions, and others usually employed in type-writers, as the indicator or alarm, indicating when a line of writing is completed or about to be completed, the feed mechanism for the platen-carriage, &c., and

other parts which are unnecessary to the understanding of my invention are of any desired or well-known construction and operation, as hereinbefore stated, and need, therefore, no further elucidation.

On the type-wheel rock-shaft S is mounted a torsion-spring S^4 , Fig. 10, one end of which is secured to the upper frame f , in which said shaft has its bearings, and the other end of said spring is secured to one of the sector-lever sleeves, which are rigidly secured to the shaft. By means of this spring the shaft S is returned to a normal position when moved out of it in writing, thus avoiding the long radial arm on the sleeve and the long retracting-spring hitherto used and connected to said arm and to the loop f' of the upper frame f , whereby said retracting-spring is also moved out of the way and the danger of its being injured in handling the paper-carriage and platen avoided.

The type-wheel W is mounted on its spindle S^3 , so as to revolve freely, and below said wheel the said spindle carries a flanged sleeve 7 , to the lower end of which is secured a pinion 8 . On the flange of the sleeve 7 is seated the stop-wheel W' , and between said wheel W' and a nut 9 and jam or lock nut 10 , screwed to sleeve 7 and which forms a bearing for the type-wheel, is secured a radial arm a , that carries a locking-pin a' , which projects into a hole in the type and stop wheels W, W' , respectively, thus locking these parts together and to the pinion 8 in a well-known manner and causing them to revolve synchronously.

The stop-wheel W' is constructed in the form of a crown ratchet-wheel having two series of teeth w^2 in number equal to the number of type-key levers L , said two series of teeth being divided by a shorter tooth w and diametrically opposite the same by a tooth w' , which is longer than the teeth w^2 , the two series of teeth being beveled in opposite directions, as shown more clearly in Fig. 15. The tooth w , which is shorter than the teeth w^2 , serves to hold the type-wheel W in a normal position or at a starting-point, while the tooth w' , which is a little longer than the teeth w^2 , serves to prevent the type-wheel from making more than one-half of a revolution in either direction under momentum when the outer or right-hand key-lever of the upper line or bank of such is depressed for positioning the letter "J," "j," or the symbol ":" for printing, requiring about half a revolution of the type-wheel W from left to right, Fig. 1, the locking-pawl then engaging the space between said longer tooth w' and the tooth w^2 on the right thereof. (See Fig. 1.) This is also the case when the extreme left-hand key-lever of the upper line or bank of such is depressed to bring the letter "Z," "z," or the symbol "," in position, which requires also about one-half of a revolution of said type-wheel in a reverse direction or from right to left. Hence in this arrangement the

left-hand series of teeth w^2 —i. e., those on the left of the shorter and longer teeth $w w'$ —correspond with the type-key levers of the left-hand group of such or on the left of the 5 spacing-lever L' , while the teeth on the right of said shorter and longer teeth correspond with the type-levers of the right-hand group, special key-levers L^2 being provided for shifting the type-wheel to print capitals, numbers, and symbols, as above explained.

It has hereinbefore been stated that the sleeve S' , having radial arm s' , that actuates the feed mechanism of the paper or platen carriage, is held against rotating independently of the type-wheel rock-shaft S through the type-wheel spindle S^3 , extending freely through suitable openings in said sleeve and shaft, and that said sleeve has an angle-arm s^3 , slotted at s^3 , Fig. 11, for the passage of a 15 dog or pawl that serves to lock said wheel when rotated to a greater or less extent in one or the other direction by type-key levers L to bring a type corresponding with the depressed key-lever into position for printing.

20 This rotation of the type-wheel is effected in a well-known manner by two arms A respectively rising from the short bail b of the two groups of type-key levers L . Each of said arms terminates in a toothed rack adapted 25 when a key-lever is depressed and through its bearing-face 2 to depress the short bail b , corresponding with the group to which the depressed lever belongs, to gear with a toothed portion 12 on toothed sector-levers B , 30 hereinbefore referred to, said levers being secured to the type-wheel rock-shaft S on the opposite sides of the pinion 8, with their toothed segments in perpetual gear with said pinion in a well-known manner.

35 The sector-levers B in their normal position abut against two projections or buffers $f^2 f^2$ on the upper frame f , and in the slot or recess between said abutments works the locking-pawl presently to be referred to, so 40 that when one of said sector-levers B is rocked by the depression of the short bail b it falls away from its buffer and rotates the pinion 8, the latter rolling down on the toothed segment of the stationary sector-lever, which 45 is held to its buffer by the reactive effect thereon of the said pinion. When, however, the type-key lever is further depressed, both sector-levers are caused to move with the rock-shaft by well-known means, and during this operation the type-key lever depresses the long bail b' by the action thereon of the bearing-surface 3 on said key-lever. As soon as the 50 type-wheel is positioned by the action of a key-lever L on bail b and the long bail b' commences to move a toothed arm A' on said bail comes into operation to lock said type-wheel.

This is effected in accordance with my invention, as follows: A locking-pawl C (shown in detail in Fig. 13) has an elongated slot c , 55 through which the rock-shaft S passes, so as to afford the necessary play to said pawl toward and from the crown ratchet-wheel W' .

The said pawl is slightly bent to one side above its slotted portion and terminates in an overhanging flange c' , which has a perforated 70 lip c^2 , and along one side of said overhanging flange extends the pawl-arm proper, c^3 , that projects through and is guided in the slot s^3 in the angle-arm s^3 of the sleeve S' , hereinabove described. By the side of the locking-pawl C and loosely mounted on the type-wheel rock-shaft S is a cam-lever D , (shown in detail in Fig. 12,) and provided with a toothed portion d , adapted to be engaged by the toothed arm A' , rising from the long bail b' , 80 said cam-lever having stepped bearing-surfaces $d' d^2$. To the left-hand buffer f^2 on the upper machine-frame f is pivoted a lever E , (shown in detail in Fig. 14,) said lever having a lateral projection e , the under face e^2 85 of which is preferably concave, so as to conform to the preferably convex bearing-surfaces $d' d^2$ of cam-lever D , though said bearing-surfaces may, if desired, be practically straight faces instead of convex and concave, 90 respectively. The upper face e^3 of lever E is convex to conform with the concave under side of the segmental flange c' on the locking-pawl C , said lever E lying normally between said flange c' and the bearing-face d' on cam-lever D . 95

When a type-key lever is depressed, the rock-shaft S is rocked toward the platen P , and therewith the type-wheel spindle S^3 , the stop-wheel W' , and the type-wheel W , the latter being at the same time revolved to the required extent by a sector-lever B . As soon as the key commences to depress the long bail b' its arm A' turns the cam-lever D in the same direction, thereby causing lever E 105 to move from bearing-surface d' on said cam-lever D to the bearing-surface d^2 , thereby lifting the lever E , and as it has bearing on the under side of flange c' in locking-pawl C said pawl is moved toward the stop-wheel W' and enters between two teeth thereof and locks it into position. This takes place immediately after a sector-lever B has positioned the type-wheel and before the rock-shaft S completes its motion toward the platen P . 115 It will thus be seen that the amplitude of the throw or travel of the locking-pawl C is a uniform one, it having to-and-fro motion in a fixed line relatively to the toothed flange on the stop-wheel W' , the return movement 120 of the pawl being effected by a retracting-spring s^5 , attached to lip c^2 on flange c' of said pawl and to the cam-lever D at d^3 , Figs. 12 and 13. The simplicity of these devices compared with those heretofore employed for the 125 same purposes will readily be understood.

In Figs. 2 to 5 I have shown the parts in their normal position and in Figs. 6 and 7 in the position when a key-lever has depressed its short bail b and is about to depress its long bail b' , the locking-arm c^3 of the locking-pawl being about to lock the stop-wheel W' , and in Figs. 8 and 9 said parts are shown in their relative positions when both short and long

bails are fully depressed and the type-wheel moved into contact with the platen P.

I have hereinbefore stated that the sleeve S', which actuates the feed mechanism for the platen-carriage and at the same time acts as a guide for the locking-arm c³ of the locking-pawl C, also carries a retarding-spring S², Fig. 11, so arranged that its bent free end will bear lightly on the vertical inner face of the toothed flange of the stop-wheel W', so that when the machine is operated rapidly or the key-levers depressed suddenly with greater force than is necessary the rotation of the type-wheel will be somewhat retarded, so as to insure its being locked as soon as it reaches the limit of its rotary motion, determined by the key struck. This spring may, however, be dispensed with, as the described mechanism has been found to operate in a perfect manner without it if at all properly handled.

Instead of operating the locking-pawl C, as above described, said pawl may be operated by means shown in Fig. 16, wherein g indicates a rod having an oblong aperture through which passes the type-wheel rock-shaft S, the rod being connected with the horizontal arm l² of a bell-crank lever l, whose vertical arm l' has a longitudinal slot l³, curved at its upper end toward said horizontal arm. The long bail b' has a projection to which is secured a pin b², extending and lying normally in the upper curved end of slot l³, so that when said long bail is depressed by a type-key lever the arm l² will push the connecting-rod upwardly, and as said long bail continues to move down the pin b² will travel in the straight portion of the slot l³ without affecting the connecting-rod g. The last-named rod carries a roller r in contact with the heel of the locking-pawl C, whereby said pawl is moved toward and into engagement with the stop-wheel W'. A spring c⁴, coiled about the stop-arm c³ and acting on a shoulder thereon or having its lower end secured thereto, while the upper end of said spring has bearing on the under side of the horizontal member of the angle guide-arm s² on sleeve S', serves to retract the pawl from the stop-wheel.

Instead of the actuating-roller r the locking-pawl C may be provided with a flange c⁵, surrounding its oblong aperture c, Fig. 17, on which flange is mounted the upper end of the connecting-rod g to move said pawl in one direction, the circular aperture in the rod being of a diameter equal to the longer diameter of the encompassing flange, as will be readily understood.

Having thus described my invention, what I claim as new therein, and desire to secure by Letters Patent, is—

1. In a type-wheel type-writer, a type-wheel stop-motion comprising a toothed stop-wheel revoluble with said type-wheel, and a locking-pawl organized to move substantially parallel to the axes of said wheels and engage the stop-wheel, for the purpose set forth.

2. In a type-wheel type-writer, a type-wheel stop-motion comprising a toothed stop-wheel revoluble with said type-wheel, and a locking-pawl organized to move substantially parallel to the axes of said wheels and engage the stop-wheel, and means for moving said pawl out of engagement with said stop-wheel, for the purpose set forth. 75

3. In a type-wheel type-writer, the combination with the type-wheel spindle, the type-wheel revoluble thereon, said spindle adapted to rock about a horizontal axis; of a type-wheel stop-motion comprising a toothed stop-wheel revoluble synchronously with the type-wheel on its spindle, and a locking-pawl, organized to rock with and move substantially parallel to said spindle into engagement with the stop-wheel, for the purpose set forth. 80

4. The combination with the type-wheel rock-shaft, the type-wheel spindle rocking with said shaft, the type-wheel, and a toothed stop-wheel revoluble synchronously on the type-wheel spindle; of a locking-pawl rocking with and having motion parallel to said type-wheel spindle on said rock-shaft, for the purpose set forth. 85

5. The combination with the type-wheel rock-shaft, the type-wheel spindle carried by and rocking with said shaft, the type-wheel and a toothed stop-wheel revoluble synchronously on said spindle, and a locking-pawl carried by the rock-shaft and having rocking motion independently thereof and with the type-wheel spindle and motion parallel to said spindle to engage the stop-wheel for the purpose set forth. 90

6. The combination with the type-wheel rock-shaft, the type-wheel spindle rocking with said shaft, the type-wheel and a toothed stop-wheel revoluble synchronously on the type-wheel spindle; of a locking-pawl rocking with and having motion parallel to said type-wheel spindle on said rock-shaft, type-key levers, and means controlled thereby for positioning the type and stop wheels and imparting the aforesaid movements to said locking-pawl when one of said levers is depressed, for the purpose set forth. 105

7. The combination with the type-wheel rock-shaft, the type-wheel spindle rocking with said shaft, the type-wheel and a toothed stop-wheel revoluble synchronously on the type-wheel spindle; of a locking-pawl rocking with and having motion parallel to said type-wheel spindle on said rock-shaft, type-key levers, means controlled thereby for positioning the type and stop wheels and imparting the aforesaid movements to said locking-pawl when one of said levers is depressed, and means for disengaging the pawl from the stop-wheel when said key-lever is released, for the purpose set forth. 115

8. The combination with the type-wheel rock-shaft, the type-wheel spindle rocking with said shaft, the type-wheel and a toothed stop-wheel revoluble synchronously on the type-wheel spindle; of a locking-pawl rock- 120

- ing with and having motion parallel to said type-wheel spindle on said rock-shaft, type-key levers, means controlled thereby for positioning the type and stop wheels and im-
5 parting the aforesaid movements to said locking-pawl when one of said levers is depressed, and means operating automatically to disengage the pawl from the stop-wheel when said key-lever is released, for the purpose set forth.
- 10 9. The combination with the type-wheel spindle, the type-wheel revoluble thereon, said spindle adapted to rock about a horizontal axis; of a type-wheel stop-motion comprising a stop-wheel having an inturned toothed flange revoluble synchronously with the type-wheel on its spindle, and a locking-pawl rocking with said spindle and moving parallel thereto into engagement with said stop-wheel, for the purpose set forth.
- 15 10. The combination with the type-wheel rock-shaft, the type-wheel spindle rocked by said shaft, the type-wheel and a toothed stop-wheel mounted to revolve synchronously on said spindle, and a locking-pawl rocking with
20 and having radial motion on the rock-shaft in the path of the teeth of said stop-wheel, and a cam-lever on the rock-shaft, a lever acted upon by said cam-lever and acting upon said locking-pawl to move it into engagement
25 with the stop-wheel; of the type-key levers and means controlled thereby and positioning the type-wheel and then actuating the aforesaid cam-lever, for the purpose set forth.
- 30 11. The combination with the type-wheel rock-shaft, the type-wheel spindle rocked by said shaft, the type-wheel and a toothed stop-wheel mounted to revolve synchronously on said spindle, and a locking-pawl rocking with
35 and having radial motion on the rock-shaft in the path of the teeth of said stop-wheel, and a cam-lever on the rock-shaft, a lever acted upon by said cam-lever and acting upon said locking-pawl to move it into engagement
40 with the stop-wheel; of the type-key levers and means controlled thereby and positioning the type-wheel and then actuating the aforesaid cam-lever, for the purpose set forth.
- 45 12. The combination with the type-wheel rock-shaft, the type-wheel spindle rocked by said shaft, the type-wheel, and a toothed stop-wheel mounted to revolve synchronously on said spindle, a locking-pawl rocked by and
50 having radial motion on the aforesaid rock-shaft, said pawl provided with a bearing-flange, a cam-lever on the rock-shaft having stepped bearing-surfaces, and a lever acted upon by said surfaces and acting upon the
55 aforesaid flange on the locking-pawl to move the same into engagement with the stop-wheel; of the type-key levers and means controlled thereby and positioning the type-wheel and then actuating the aforesaid cam-lever, for
60 the purpose set forth.
- 65 13. The combination with the type-wheel rock-shaft, the type-wheel spindle rocked by said shaft, the type-wheel, and a toothed stop-wheel mounted to revolve synchronously on said spindle, a locking-pawl rocked by and having radial motion on the aforesaid rock-shaft, said pawl provided with a bearing-flange, a cam-lever on the rock-shaft having stepped bearing-surfaces, and a lever acted upon by said surfaces and acting upon the aforesaid flange on the locking-pawl to move the same into engagement with the stop-wheel; of the type-key levers, means controlled thereby and positioning the type-wheel and then actuating the aforesaid cam-lever, and a coiled spring connecting the locking-pawl and cam-lever, for the purpose set forth.
14. The combination with the type-wheel rock-shaft, the type-wheel spindle carried thereby and rocking therewith, the type-wheel and a toothed stop-wheel having its teeth formed in an inturned circular flange and divided into two sets having their faces beveled in opposite directions, said wheels mounted to revolve synchronously on the type-wheel spindle, and a locking-pawl carried by and having independent motion on the type-wheel rock-shaft, said pawl rocking with the type-wheel spindle and having motion parallel thereto, of type-key levers, and means controlled thereby to position the type and stop wheels, rock the pawl, and move it into engagement with the toothed flange of the stop-wheel when one of said levers is depressed, for the purpose set forth.
15. The combination with the type-wheel rock-shaft, the type-wheel spindle rocked by said shaft, the type-wheel, and a stop-wheel having a toothed circular flange divided into two series of teeth by a longer and a shorter tooth, said series of teeth having their faces beveled in opposite directions and said stop and type wheels mounted to revolve synchronously on said spindle, and a locking-pawl having radial motion on the rock-shaft in the path of the teeth on the stop-wheel; of the type-key levers, means controlled thereby to position the type-wheel and then move the pawl into engagement with the stop-wheel, and means not controlled by said key-levers to move said pawl out of engagement with the stop-wheel, for the purpose set forth.
16. The combination with the type-wheel rock-shaft, the type-wheel spindle rocked thereby, the type-wheel and the stop-wheel W^2 having two series of teeth w^2 divided by the shorter tooth w , and the longer tooth w' , said two wheels mounted to revolve synchronously on said spindle, the locking-pawl C and cam-lever D constructed as described and mounted on the rock-shaft, and the lever E interposed between the cam-surfaces of the cam-lever and the bearing-flange on the locking-pawl; of the type-key levers, the short bails b actuated thereby, and means controlled by said short bails to position the type-wheel, the long bail b' actuated by said key-

levers, and a toothed arm on said long bail adapted to gear with a toothed portion of the cam-lever, for the purpose set forth.

17. The combination with the type-wheel 5 rock-shaft, the type-wheel spindle rocked thereby, the type-wheel, and a toothed stop-wheel mounted to revolve synchronously on said spindle, a locking-pawl having radial motion on the rock-shaft and a guide for said 10 pawl rocked by the shaft; of the key-levers, means controlled thereby to position the type-wheel and then move the locking-pawl radially of the rock-shaft into engagement with the stop-wheel, and means for moving said 15 pawl out of engagement with the stop-wheel on the release of a type-key lever, for the purpose set forth.

18. The combination with the type-wheel rock-shaft, the type-wheel spindle rocked 20 thereby, the type-wheel, and a toothed stop-wheel mounted to revolve synchronously on said spindle, a locking-pawl having radial motion on the rock-shaft and a guide for said pawl rocked by the shaft; and carrying a re- 25 tarding-spring in perpetual frictional contact with said stop-wheel; of the key-levers, means controlled thereby to position the type-wheel and then move the locking-pawl radially of the rock-shaft into engagement with the stop- 30 wheel, and means for moving said pawl out

of engagement with said stop-lever on the release of a type-key lever, for the purpose set forth.

19. The combination with the rock-shaft S, 35 the type-wheel spindle S³, the stop-wheel W and the locking-pawl C; of the sleeve S' rocking with the shaft S and having the radial arm s' and the angle radial arm s² provided with a guide-slot s³ for the locking-arm c³ of said pawl C, substantially as and for the purpose set forth.

20. The combination with the rock-shaft S, 40 the type-wheel spindle S³, the stop-wheel W and the locking-pawl C; of the sleeve S' rocking with the shaft S and having the radial arm s' and the angle radial arm s² provided with a guide-slot s³ for the locking-arm c³ of said pawl C, and the segmental spring S² secured to said slotted arm and having bearing 45 on the inner face of the toothed flange of said stop-wheel, substantially as and for the purpose set forth.

In testimony that I claim the foregoing as my invention I have signed my name in presence of two subscribing witnesses.

CHARLES THOMAS POWERS.
